REINFORCED CONCRETE AND TILE WALL CONSTRUCTION

Cassius M. Carrier, McKeesport, Pa.

Application April 30, 1954, Serial No. 426,847

1 Claim. (Cl. 72—30)

This invention relates to a building wall construction, and, more particularly, to a reinforced concrete and tile wall construction which can be readily and easily erected at the building site without the use of mortar to provide a wall of amazing strength.

An outstanding disadvantage of conventional wall constructions is that they involve considerable labor in erecting the wall, block by block, such as in the case of all-concrete walls, also the erection of such walls is very time consuming and expensive.

An object of my invention is to provide a wall construction which is devoid of the above named disadvantages of conventional wall constructions, and more particularly to provide a combination reinforced concrete and tile wall construction.

A more specific object of my invention is to provide a wall construction of steel and concrete rib construction with a tile filler, wherein various patterns of tile may be provided so as to permit a greater or smaller ratio of tile area to concrete area, depending on the strength of wall desired.

Other objects and advantages of my invention will become more apparent from a study of the following description taken with the accompanying drawing wherein:

Figure 1 is a fragmentary plan view of a corner portion of a reinforced concrete and tile wall embodying the principles of my invention;

Figure 2 is a vertical elevational view of the reinforced concrete and tile wall shown in Figure 1, but also showing an additional door portion, and wherein the top portions of the forming boards are shown broken away to more clearly illustrate the concrete pillar portions formed thereby;

Figure 3 is a cross-sectional view taken along III—III of Figure 2;

Figure 4 is a vertical cross-sectional view of a part of a wall and steel joist combination showing how my invention is adapted to support such joist;

Figure 5 is a modification of my invention involving two horizontal rows of vertically disposed tiles instead of one, and located between the horizontally disposed rows of tile as shown in Figure 2 and;

Figure 6 is a second modification wherein three vertically stacked tiles are provided intermediate the horizontally disposed tiles.

Referring more particularly to Figures 1 and 2, numeral 1 denotes a plurality of horizontally disposed hollow tiles, such as those with scored outer surfaces, which are spaced about 4" apart with their inner cellular openings being in alignment or registry in a horizontal direction. Numeral 3 denotes vertically disposed tiles which are sandwiched between the horizontally disposed tiles 1 and the cellular openings of which extend vertically. Upon each vertically extending horizontal row of tile 3 there is stacked another horizontal row 1 of tile, that is, with horizontally extending openings. After a plurality of horizontal courses of tile have been laid, forming boards 5 are erected and may be temporarily held in

2

place by angularly extending braces (not shown). Boards 5 have a width of greater than the 4" spacing between vertical rows of tiles, as shown more clearly in Figure 1. Forming boards 5 are disposed in opposed relationship on opposite sides of the wall as shown more clearly in Figure 1. To one of the inner surfaces of opposed pairs of forming boards 5 there is lightly nailed a hard wood strip 6 with beveled edges to be embedded in the concrete pillars 2 after the concrete is poured between vertical rows of tile. The purpose of strips 6 is to provide the surface onto which to nail or otherwise attach insulation or trim to the inside of the building. Strips 6 may extend from floor to ceiling. Wood stringers 7 and 8 are mounted in spaced, horizontally extending parallel relationship on the outside surface of opposing forming boards 5 so as to provide horizontal alignment of the various vertical rows of tile. Stringers 8 may be mounted by means of wires 11 which are looped therearound and through staggered small holes formed in the forming boards 5.

After the wall is completely erected, that is, with tile and forming boards, vertical reinforcing rods 9 are extended through the vertical spaces between vertical rows of tile. Horizontal reinforced rods 10 are extended through horizontal registering openings of alternate rows of tile 1. Thereafter the vertical spaces are filled with concrete to form vertical concrete pillars 2. As the concrete flows vertically downwardly, confined by forming boards 5 and 6, it will flow along the side of the outer end surfaces of the vertically extending tiles 3, but will flow laterally through the horizontal openings in the alternate horizontally extending courses of tile 1, so as to provide a grid-like formation of concrete. The ends of rods 10 are anchored to 4" x 4" anchors 12, the lower portion of which are embedded in the footer F at the corners. Such anchored ends of rods 10 are arranged at spaced heights of the angle iron 12. Angle iron 12 may be provided with holes through which the end portions of reinforcing rods 10 may extend, or such holes may be merely burned in. Moreover, reinforcing rods 10 may be prestressed, such as by bending the end portions 10a thereof at right angles against a flange of angle iron 12, and applying turn-buckles at the opposite ends. Likewise the vertical reinforcing rods 9 may be prestressed.

As shown in Figure 2 a door frame may be built in so as to be completely surrounded by reinforced concrete.

Figure 4 shows a structure somewhat similar to that in Figures 1, 2 and 3 comprising tiles 1 with horizontally extending openings and tiles 3 with vertically extending openings, arranged in alternation. Horizontal reinforcing rods 10 are embedded in the concrete and which extend through the horizontally registering tile openings. A steel floor joist 16 is provided and its end is supported, as shown, with a horizontal reinforcing rod 10 extending through a hole thereof if so desired. A concrete floor 17 is laid thereon and covered with a floor of linoleum or hard wood 18 or the like. To facilitate laying of floor 18 wood strips similar to strips 6, shown in Figure 1 may be embedded and disposed in spaced horizontal rows in the top portion of concrete floor 17.

Figure 5 shows a modification which is similar to the construction shown in Figures 1 and 2 except that double courses of tile 3, with vertical openings, are provided instead of a single course for purposes of economy of steel and concrete. That is to say, there are alternate horizontally disposed courses 1 of tile with horizontal passages, and there are alternate double courses of tile having vertical passages. The resulting structure is still a grid-like reinforced concrete structure with a tile filler.

Figure 6 shows a further modification wherein instead

of doubly stacked tiles 3, there are three stacked tiles provided to provide a triple course and a smaller ratio of concrete than tile in situations where wall strength may be sacrificed slightly.

Similarly, other arrangements of tile may be used such as stacks of four or a larger number instead of 1, 2 or 3. The vertical rows may be double or triple, etc., instead of single, in thickness. Likewise instead of providing horizontally disposed tiles in single horizontal courses, as shown, they may be stacked so as to provide two or more adjoining horizontal courses with horizontal passages. Thus the arrangement may be two horizontal courses of tile and two or more adjoining vertically stacked courses etc. Or in some instances, all the tile may be disposed with their openings extending horizontally and with none extending vertically. The important underlying principle in stacking the tile is that they should be symmetrically stacked so that in the case of tiles with horizontal openings, the various tiles of any one horizontal course will have their openings in alignment. The reason, of course, is to allow the horizontal reinforcing rods 10 to extend through the entire horizontal course. Likewise vertically stacked tiles with vertical openings will have their vertical openings in alignment. Of course, in situations where some or all of the metal reinforcing may be eliminated the symmetry is no longer indispensable, and alignment of the tile openings is no longer required.

Tile 3, which have vertical passages, may be filled with insulating material, if desired, in cases where heat or cold insulation is important.

Thus it will be seen that I have provided an efficient building wall construction in the form of a combined reinforced concrete ribbed construction with a tile filler, wherein various arrangements of tile may be made to provide a greater or lesser amount of tile in relation to concrete, resulting in a grid-like reinforced concrete structure with tile filler, and wherein such walls may be erected without the necessity of mortar, and with great ease and speed, involving simply the erection of vertically spaced preforming boards on opposite sides of the wall for bridging the spaces between vertical rows of tile reinforcing with rods, then pouring concrete; furthermore, I have provided a reinforced concrete and tile building wall construction in which the reinforcing rods

may be embedded in concrete and prestressed so as to form a wall of amazingly high strength.

While I have illustrated and described several embodiments of my invention, it will be understood that these are by way of illustration only, and that various changes and modifications may be made within the contemplation of my invention and within the scope of the following claim.

I claim:

10 A reinforced concrete building wall with tile filler comprising, in combination, a plurality of spaced, vertically extending concrete columns, and a plurality of vertical columns of tile completely filling the space therebetween, each tile column being arranged in a plurality of horizontal courses, wherein each course consists of a single tile unit spanning the space between the adjacent concrete columns, certain of said horizontal courses consisting of the tile units having aligned cellular openings extending horizontally of the wall and other of said horizontal courses of each tile column consisting of tile units having aligned cellular openings extending vertically, certain of said horizontally extending aligned cellular openings having concrete therein reinforced with metal rods extending horizontally through the adjacent columns and continuously through the aligned cellular openings throughout a major portion of the wall.
